UNITED STATES PATENT OFFICE.

JAMES LOUIS HEIMRICH, OF TIFFIN, OHIO.

TEMPLATE TOOL.

Application filed September 6, 1921. Serial No. 498,627.

To all whom it may concern:

Be it known that I, JAMES L. HEIMRICH, a citizen of the United States, residing at Tiffin, in the county of Seneca and State of Ohio, have invented certain new and useful Improvements in Template Tools, of which the following is a specification.

This invention relates to an adjustable tool for use as a template.

10 The primary object of the invention is the provision of a template tool including adjustable marking blades for cooperative action in designating working operations to be performed on plates, boards and the like, wherever a template is ordinarily used.

20 A further object of the invention is the provision of a template tool of the above described character, in which the blades are so adjusted as to provide templates functioning within a wide range of adjustment.

Other objects and advantages will be apparent during the course of the following detailed description.

25 In the accompanying drawing, forming a part of this specification, and in which similar reference characters designate corresponding parts throughout the several views.

30 Figure 1 is a perspective view of the improved template tool.

Figure 2 is a cross sectional view taken on the line 2—2 of Figure 1.

35 Figure 3 is a cross sectional view taken on the line 3—3 of Figure 2.

Figure 4 is a plan view of the improved template tool, showing the same in position upon a piece of work for marking purposes.

40 Figure 5 is a plan view of the piece of work illustrated in Figure 4 and showing the method of marking the same.

Figure 6 is a plan view of the improved template tool showing the same in an adjusted position other than that illustrated in Figure 4 and in connection with a piece of work to be marked.

45 In the drawing, wherein for the purpose of illustration is shown a preferred embodiment of this invention, the letter A designates the improved template tool, including the blades B and support or guide frame C.

50 The blades B are all of identical formation, the same being of any suitable length, consistent with the class of work for which the template is desired. The blades B are provided with the bevelled longitudinal

edges 10. Each blade B is provided adjacent one end 11 with a plurality of equi-spaced perforations 12, arranged centrally of the blade width, and extending for substantially one-half of the length thereof. 60 Graduations 14 are provided upon both upper and lower surfaces of each blade B extending transversely of the blade B in parallel alignment, the graduations 14 intersecting the center of the apertures 12. However, the graduations 14 extend the entire length of the blades B from the end 15 to the end 11. The extreme end 15 is likewise provided with an aperture 17, 65 extending through the thickness thereof, the center of which designates the last graduation mark 14 upon the end 15 of said blade B; said aperture 17 being positioned a predetermined distance with respect to the extreme aperture 12 upon the end 11. 70

The supporting or guide frame C is preferably polygonal in formation. The outer surfaces 20 and 21 of the frame C are provided with guide ways 23 and 24, respectively cut downwardly therein, the entire width of the frame C; said guideways 23 and 24 being arranged with their longitudinal axes at exactly 90° to each other. The inside edges of the guide ways 23 and 24 80 are undercut, in order that said guide ways 23 and 24 may receive the template blade B in dove tail manner for sliding in said frame C. The guideways 23 and 24, in depth extend for substantially one half the 85 thickness of the material of frame C, and since the same intersect, an aperture in said frame C is provided. Graduation marks 26 in alignment with each other are provided at right angles to the guide way 23 90 therein and upon the top surface 20, which are adapted for alignment with respect to the graduation marks 14 upon the blade B which slides in the groove way 23, to determine the position of said blade B with respect to the frame C. Likewise, the opposite surface 21 of the frame C is provided with indicating graduations 28 in alignment and at right angles to the guide way 24 in said side 21, whereby said graduations 100 28 may be aligned with the graduations 14 upon the template blade B adapted for sliding in the guide way 24, to determine the position of apertures with respect to said frame C. When a graduation 14 of 105 the blade B is arranged in alignment with the graduation 26 upon the surface 20; and

2
a graduation 28 of the frame C aligns with work piece D, the circles or indicating a graduation 14 of the blade B which lies in the groove 24, the apertures 12 of the blades B whose graduation marks 14 are 5 in alignment with the indicating marks 26 and 28, will be concentrically aligned. In this manner, the respective positions of any apertures 12 of the blade B can be determined with respect to each of said blades, 10 as well as with respect to the frame C.

Set screws 30 are provided in the surface 20 of the frame C adapted for adjustment 15 in apertures through the thickness of said frame C for clamping purposes against a bevelled edge 10 of the blade B which operates in a sliding manner in the guideway 23. Similarly, set screws 31 are provided in the surface 21 of the frame C operating 20 in counter-sunk apertures through the thickness of the frame C and adapted for clamping purposes against the bevelled edge 10 of a template plate B operating in the guideway 24.

In operation with a piece of work D, such 25 as a steel plate which is to be marked for punching or stamping purposes, the template tool A is adjusted as to the blades B and frame C, in order that the desired marks may be struck upon an outer surface of the 30 piece of work D. As illustrated in Figure 1 of the drawings, a template tool has been provided, the blades of each of which measure slightly over six inches, and which have been graduated and apertured accordingly 35 and as above described.

Assuming that it is desired to stamp, tap, or drill the piece of work D with four apertures through the thickness thereof, to 40 designate a perfect square of six inches. The first operation would be that of adjusting the blades B in the frame C until the zero mark of each would coincide with the indicating marks 26 and 28 of the frame C, at which position the apertures 12 in 45 said blades B as designated by the zero marks in said blades would align. As illustrated in Figure 4, the template is next laid upon the upper surface of the piece of work D, and the operator by inserting 50 a scribing element, such as a pencil through the aligning apertures 12 as concentrically arranged in the frame C and bearing against the surface of the work D would 55 scribe the circle or mark 35 thereon. The 55 graduations upon the blade B indicate the next aperture through which the operator should scribe upon the work D, and which in the example given, would be the apertures 17 in said blades B. By inserting 60 the scribing element through the apertures 17 and bearing upon the surface of the

work piece D, the circles or marks 36 and 37 are provided. This will give free corner points designating the apertures to be drilled in the piece of work 65 D. By now shifting the template A in its set position into the dotted lines as illustrated in Figure 5, whereby an end aperture aligns with the mark 35 and the aligning apertures 12 of the blades B are arranged over the mark 37, the fourth mark 70 38 may be obtained, as can readily be seen from Figure 5 of the drawings.

Only one half of each of the blades B 75 need be apertured, due to the adjustment of the blades B in the frame C, to meet the demands of any class of work.

Various changes in the shape, size and arrangement of parts may be made to the 80 form of the invention herein shown and described, without departing from the spirit of the invention or the scope of the claims.

I claim:

1. A template tool, comprising in combination, a supporting frame having opposite faces thereof provided with grooves forming guide ways extending at right angles to each other in crossed relation and meeting at the central portion of the frame, and template blades for sliding in said guide ways and having perforations adapted to be brought into registration one with another.

2. A template tool, comprising a plurality of template blades having spaced perforations therein, and means slidably mounting said blades in crossed relation for longitudinal movement at right angles to each other for bringing a selected perforation 95 of one blade into registry with a selected perforation of the other blade so that they may be relatively set for marking an article 100 through the selected perforations.

3. As an article of manufacture, a guide frame provided upon the top and bottom faces thereof with guide slots positioned at right angles to each other and in intersecting relation to provide an opening transversely thru said frame.

4. A template tool, comprising in combination a guide frame having an opening therein and provided upon the top and bottom faces thereof with guide slots positioned at right angles to each other, and template blades for sliding in said slots and having spaced apertures therein for substantially one half the longitudinal length thereof and adjacent one end thereof, and provided with a single aperture in the 115 other end.

JAMES LOUIS HEIMRICH.
